UNITED STATES PATENT OFFICE.

LEONIDAS BAXTER, OF DAYTON, OHIO, ASSIGNOR TO THE THOMAS MANUFACTURING COMPANY, OF DAYTON, OHIO, A CORPORATION OF OHIO.

DESIGN FOR A HYDROCARBON-LANTERN.

47,770.

Specification for Design. Patented Aug. 31, 1915.

Application filed March 25, 1915. Serial No. 17,067. Term of patent 14 years.

To all whom it may concern:

Be it known that I, LEONIDAS BAXTER, a citizen of the United States, residing at Dayton, in the county of Montgomery and State of Ohio, have invented a new, original, and ornamental Design for a Hydrocarbon-Lantern, of which the following is a specification, reference being had to the accompanying drawing, forming part thereof.

The figure is an elevational view of a

hydrocarbon lantern, showing my new design.

I claim:

The ornamental design for a hydrocarbon lantern, as shown.

LEONIDAS BAXTER.
